To all whom it may concern:

Be it known that I, Tora Coleman, a citizen of Latvia, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 3 is a rear view of the jacket unit of the dress ensemble shown in Figure 1.

Figure 4 is a rear view of the jacket unit of the dress ensemble shown in Figure 1.

The characteristic feature of my design resides in the combination on the ensemble disclosed of the tucked skirt and tucked jacket having plain borders, in association with a seamed and printed waist section, arranged in the manner shown.

I claim:

The ornamental design for a dress ensemble, substantially as shown, and described.
